United States Patent Office

Des. 232,749

Patented Sept. 10, 1974

232,749

MUSICAL TOY

Michael R. Meyers, 18 Lyncrest Drive, Munsey, N.Y.
12123, and Michael Langieri, 8 Cedar St., Butler, N.J.
07405

Filed Oct. 2, 1972, Ser. No. 294,336

Term of patent 14 years

Int. Cl. D21—01

U.S. Cl. D34—15 C

Fig. 1.

Fig. 2.

Fig. 3.

Fig. 4.

FIG. 1 is a perspective view of a musical toy showing our new design;

FIG. 2 is a front elevational view;

FIG. 3 is a top plan view; and

FIG. 4 is a left-side elevational view.

The bottom surface, not shown, is substantially plain and unornamented.

We claim:

The ornamental design for a musical toy, as shown and described.
